CLAIM

The ornamental design for a heliodon-type device, as shown and described.

DESCRIPTION

FIG. 1 is a perspective view of my heliodon-type device showing my new design;

FIG. 2 is a front view of the device illustrated in FIG. 1 on an enlarged scale;

FIG. 3 is a right side view of the device illustrated in FIG. 1 on an enlarged scale;

FIG. 4 is a rear view of the device illustrated in FIG. 1 on an enlarged scale;

FIG. 5 is a left side view of the device illustrated in FIG. 1 on an enlarged scale;

FIG. 6 is a top view of the device illustrated in FIG. 1 on an enlarged scale;

FIG. 7 is a bottom view of the device illustrated in FIG. 1 on an enlarged scale;

FIG. 8 is a perspective view of an alternative embodiment of my device;

FIG. 9 is a perspective view of still another alternative embodiment of my device;

FIG. 10 is a front view of the device illustrated in FIG. 9 on an enlarged scale;

FIG. 11 is a right side view of the device illustrated in FIG. 9 on an enlarged scale;

FIG. 12 is a rear view of the device illustrated in FIG. 9 on an enlarged scale;

FIG. 13 is a left side view of the device illustrated in FIG. 9 on an enlarged scale;

FIG. 14 is a top view of the device illustrated in FIG. 9 on an enlarged scale; and

FIG. 15 is a bottom view of the device illustrated in FIG. 14 on an enlarged scale.
